UNITED STATES PATENT OFFICE

144,214

DESIGN FOR A TAPE DISPENSER

Harry Preble, Jr., New York, N. Y., assignor to International Plastic Corporation, Morristown,
N. J., a corporation of Illinois

Application October 6, 1945, Serial No. 122,607

Term of patent 14 years

(Cl. D74—1)

To all whom it may concern:

Be it known that I, Harry Preble, Jr., a citizen of the United States, residing at New York, in the county of New York and State of New York, have invented a new, original, and ornamental Design for a Tape Dispenser, of which the following is a specification, reference being had to the accompanying drawing, forming a part thereof.

In the drawing:

Figure 1 is a front view of a tape dispenser
embodying my design;

I claim:

The ornamental design for a tape dispenser, substantially as shown.
